UNITED STATES PATENT OFFICE.

AMOS B. KEITH, OF BOSTON, ASSIGNOR TO WILLIAM W. KEITH, TRUSTEE,
OF NEWTONVILLE, MASSACHUSETTS.

ILLUMINATED SIGN OR NAME-PLATE.

SPECIFICATION forming part of Letters Patent No. 258,304, dated May 23, 1882.

Application filed February 4, 1882. (No model.)

To all whom it may concern:

Be it known that I, AMOS BLOOD KEITH, a citizen of the United States, residing at Boston, in the county of Suffolk and State of Massachusetts, have invented certain new and useful Improvements in Illuminated Signs or Titles; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to signs, name-plates, and other plates marked with characters which are phosphorescent; and it consists in combining with a plate having a layer of phosphorescent material laid thereon a second plate having characters stenciled in it, and a glass facing which protects the phosphorescent material behind these stenciled openings, but allows it to be seen in the form of illuminated characters.

The drawings accompanying this specification represent, in Figure 1, a perspective view, and in Fig. 2 a section, of a door-plate containing my invention.

I have represented in said drawings a door-plate wherewith to illustrate the novel feature of my invention in one of the various forms in which it may be adapted to useful purposes.

A represents the door-plate, the front face of which has a surface of luminous paint applied to it, such surface being represented by the heavy black line B in Figs. 1 and 2.

C represents a sheet of thin metal or other suitable material, having cut in it the requisite letters and figures or other desired characters after the manner of an ordinary stencil-plate, this sheet or plate C being secured to the front of the door-plate A in a proper manner, and preferably covered with a protecting glass plate, D. The luminous background C is sufficiently visible through the apertures forming the characters of the door-plate to render such address plainly perceptible in the darkness, while during the day-time it presents sufficient contrast with the surrounding 50 surface to also be plainly visible.

Street-signs, clock-dials, and mottoes for the embellishment of apartments, and in fact many forms of titles or addresses composed of

letters or figures, or the same and some accompanying character, are capable of being illuminated by my method.

I am aware that it is not broadly new to provide sign-plates and similar articles with phosphorescent characters; also, that it is not broadly new to protect such characters by a facing of glass; also, that stenciled sign-plates are not broadly new. I therefore do not claim any of the above features, broadly, nor the combination of one with either of the others.

My construction, however, protects the luminous material more satisfactorily than any which had previously been known in the art. The plate on which it is painted and the stenciled plate inclose it between them, so that the only spots that could be exposed are those opposite the stenciled letters, and these are protected by the glass plate or facing. Of course the letters are as luminous as those of any other phosphorescent sign, while the greater part of the luminous material is protected in front by two thicknesses of shielding substances, one being of metal, the other of glass.

My sign-plate can be used for a number of different illuminated signs without changing the illuminated surface or making any marks thereon. It is only necessary to substitute one stenciled plate for another, and the characters of the sign are correspondingly changed. Without the stenciled plate the same result could only be effected by repainting the illuminating surface at each change of characters. Therefore

What I claim as new, and desire to secure by Letters Patent, is—

In combination, with a plate having a facing of luminous material applied thereto, a second opaque plate having characters cut through or stenciled in it and covering said luminous material, and a transparent plate, sheet, or facing which covers said stenciled characters as well as the remainder of the stenciled plate, but allows the light of the material behind to shine through in the form of illuminated characters, substantially as set forth.

In testimony whereof I affix my signature in presence of two witnesses.

AMOS B. KEITH.
